HOLSTER

Hugh D. Adair, College Park, Ga.

Application April 23, 1948, Serial No. 22,789

1 Claim. (Cl. 224—2)

1

This invention relates to a holster, and more particularly to holsters of the type used for carrying pistols and revolvers.

According to my invention, the holster has a stiffening portion running along the back side of the holster which not only serves for holding the holster against upward movement when the weapon is withdrawn, but which also serves for supporting the holster from a belt. The method of attaching the holster to the belt is such that the holster may be removed from the belt without unbuckling the belt or removing the belt from the waist. This type of holster is particularly designed for use by detectives, deputy sheriffs and other peace officers who must wear a heavy service type revolver under a coat, but it is also quite advantageous for use by all persons who must carry a weapon of this type.

The holster which I have invented also includes a novel cartridge pocket preferably located on the lower portion of the holster, and formed as an integral part of the holster, thus permitting the wearer to have readily at hand a full reload for his weapon, without the necessity for carrying extra cartridges in belt loops or pockets separately attached to the belt which supports the holster, or in the pockets of his coat.

It is a primary object of the invention to provide a holster for revolvers or pistols which has a stiffening back which serves not only to hold the holster against upward movement when the weapon is withdrawn, but also serves for attaching the holster to a belt.

A further object of the invention is to provide a holster having a stiffening back portion which also serves for attaching the holster to the belt. The arrangement is such that the holster may be mounted on or removed from the belt without removal of the belt from the wearer, or unbuckling of the belt.

It is a still further object of the invention to provide a holster having a novel reload pocket located on the lower portion of the holster.

These and other objects of the invention will be apparent from the following specification and the accompanying drawing, in which

Figure 1 is a perspective view showing a holster made according to a preferred form of the invention, the stiffening back of the holster being integral with the body of the holster;

Figure 2 is a front elevational view of the holster shown in Figure 1;

Figure 3 is a view similar to Figure 2 but showing a modified form of the invention; and

2

Figure 4 is a back view of the holster shown in Figure 3.

In the embodiment of the invention shown in Figures 1 and 2, the holster has a body portion 10 which is formed of a single piece of leather bent back upon itself at the front edge 11 and stitched along the rear edge 12. The back wall 13 of the body of the holster is bent downwardly upon itself at 14, and extends substantially the entire length of the body of the holster, as is shown clearly in Figure 2. This downwardly extending portion 15 of the rear wall 14 of the body of the holster forms a stiffening back, and it is also obvious that a belt passed beneath the bend 14 will support the holster.

In order to define a path for the belt, and to assure that the holster is maintained in substantially a fixed position relative to the belt, two snaps 16 and 17 located near the front and rear edges of the holster provide means for attaching the stiffening flap 15 to the rear wall 13 of the body of the holster. When these snaps are fastened together, the passage above the snaps and below the fold 14 accommodates a belt, and the snaps 16 and 17 are placed along a line substantially parallel with the fold 14 so that little if any leeway is provided for swinging of the holster about the belt. The snaps hold the holster against upward movement relative to the belt when the weapon is withdrawn.

Another snap 18 is provided on the inner surface of stiffening back 15, and a flap 19 attached to the inner surface of the lower end of the holster body is passed around the lower end of the stiffening portion 15 to fasten on to snap 18. Flap 19, when engaged with snap 18, maintains the holster body substantially coextensive with the stiffening flap 15 and therefore close to the body of the wearer. An extra layer 20 of leather or other suitable material may be attached to the flap 15 to impart additional stiffness to flap 15 which maintains the holster body 10 against upward movement when the weapon is withdrawn. The surface of layer 20 may be roughened to provide a frictional anchorage of the holster against the adjacent layer of clothing.

The need for such layer 20 will depend upon the degree of natural stiffness of the flap 15, since a naturally stiff flap 15 will need no additional stiffening to perform efficiently its function of holding the holster against upward movement and against flapping movement.

It will be clear that the holster may be quite simply placed on a belt when the belt is being worn by simply disengaging snaps 16, 17 and 18,

sliding the stiffening flap 15 downwardly inside the belt until the belt rests against the inner surface of fold 14, and then fastening the snaps together. Removal is accomplished by merely disengaging the snaps and sliding the holster upwardly until the flap 15 is withdrawn from the inner surface of the belt. Thus the belt need not be unbuckled or removed when the holster is to be placed on the wearer or removed.

The holster also has the additional feature of a reload pocket 22 which is formed by a piece of leather which is attached at the rear edge of the holster body at 23, and is passed about the front edge of the body at 24. A second piece of leather 25 provides an inner wall for the pocket, and also provides flaps 26 and 27 at the upper and lower openings of the pocket. By means of the upper flap 26, cartridges may be readily inserted into the pocket, while the lower flap 27 permits ready removal of the cartridges by simply flipping the flap open with the thumb and permitting the cartridges to drop into the palm of the hand.

The forward edge of inner piece 25, as well as the forward edge of outer pocket piece 24, pass about the front edge 11 of the lower portion of the holster body, and are attached to the inner surface of the body by stitches which are not shown. As shown in Figure 2, the two pieces 24 and 25 may pass over flap 19, and a single row of stitches may pass through the two pieces 24 and 25, as well as the flap 19, thus making a unitary structure which is manufactured with a minimum of sewing.

By placing the pocket 22 at the lower end of the holster, the over-all thickness of the holster at the position of the pocket is maintained at a minimum as will be obvious from Figure 2. Attachment of the pocket to the upper portion of the holster body would bring the pocket to a position adjacent the thickest part of the revolver, so that an unnecessary bulge would be caused in the clothing of the wearer.

A modified form of the invention is shown in Figures 3 and 4. In this embodiment, the holster body 30 has a back portion 31 which provides stiffening, while at the same time providing means for attaching the holster to a belt. The back 31, instead of being integral with the holster as in the embodiment of Figures 1 and 2, is separate and is attached along its upper edge to the upper edge of the holster body by means of a row of stitches, staples, or other attaching means 32. In this embodiment, the stiffening back 31 is provided with two snaps 33 and 34, and terminates a short distance below the flaps, instead of extending the entire length of the holster. This modification provides a slightly lighter and less bulky construction than the modification of Figures 1 and 2, and the flap or stiffening back 31

5 serves quite well for retaining the holster against upward movement when the weapon is withdrawn, as well as serving for attachment of the holster to a belt without necessitating removal or unbuckling of the belt when the holster is to be attached or removed from the wearer's belt. Obviously, the construction of Figures 1 and 2, in which the stiffening back 15 is integral with the body of the holster, could be made as in Figures 3 and 4, with the back terminating at a point just below snaps 16 and 17. Also, the embodiment of Figures 3 and 4, in which the back 31 is a separate piece from the holster body 30, could be made with the stiffening back 31 extending the full length of the holster, and with a snap similar to the snap 18 holding a bottom flap member similar to flap 19.

The holster which I have described above is susceptible to numerous modifications without departing from the inventive concept, and it is my intention to cover all forms of such modifications falling within the scope of the appended claim, and outside the scope of the prior art.

I claim:

25 A holster for side arms to be carried on a belt comprising a body portion for receiving the weapon; a relatively stiff back member joined to the extreme upper end of the holster body, said back member extending substantially the entire length of the holster; disengageable fastening means spaced below said upper end for removably joining said back member to said holster body and for defining a belt-receiving space only wide enough to receive the belt between the fastening means and the upper end of the holster; means for removably attaching the lower end of the holster body to the lower end of the back member to increase the stiffening action; a strap attached to the inner surface of the lower end portion of the holster body; a fastener on the inner surface of said back member for engagement by said strap; a piece of leather positioned about the bottom portion of the holster body to form a cartridge pocket, and stitching attaching both said strap and pocket piece to the holster body.
